(57) **CLAIM**

We claim the ornamental design for an aircraft, as shown and described.

DESCRIPTION

FIG. 1 is a side view for an aircraft, showing the new design, a side view of the reverse side is a mirror image of the illustrated side;

FIG. 2 is a front view of the aircraft;

FIG. 3 is a front view of a starboard portion of the aircraft;

FIG. 4 is a front view of a port portion of the aircraft;

FIG. 5 is a rear view of the aircraft;

FIG. 6 is a rear view of a starboard portion of the aircraft;

FIG. 7 is a rear view of a port portion of the aircraft;

FIG. 8 is a top view of the aircraft;

FIG. 9 is a top view of a starboard portion of the aircraft;

FIG. 10 is a top view of a port portion of the aircraft;

FIG. 11 is a bottom view of the aircraft;

FIG. 12 is a bottom view of a starboard portion of the aircraft; and,

FIG. 13 is a bottom view of a port portion of the aircraft. The broken lines shown in the drawings illustrate portions of the aircraft that do not form part of the claimed design.
